RECTIFIER FOR TELEVISION SIGNALS

Kurt Schlesinger, Berlin, Germany, assignor, by
mesne assignments, to Loewe Radio, Inc., a
corporation of New York

Application March 13, 1937, Serial No. 130,718
In Germany March 19, 1936

2 Claims. (Cl. 178—7.3)

The present invention relates to television circuit arrangements and more particularly to television rectifying circuit with an after-connected amplifier-stage and most effective suppression of 5 the carrier-frequency oscillations.

The object of a rectifier in respect of the modulated ultra-short wave or the modulated intermediate-frequency wave of a television superhet is as follows: Inertialess operation in demodulating up to maximum frequency of the image, the image-point traversing period; further, at least linear response to increasing amplitudes of the carrier wave, and preferably more than linear response, i. e., increasing slope of the characteristic curve in the case of increasing amplitudes, as this is favourable as regards the reproduction of half-tones in white and as far as possible, complete elimination of traces of carrier frequency-oscillations in the demodulated 15 circuit for the purpose of avoiding the danger of reaction coupling and interfering stripes in the image. These three conditions must be fulfilled in a rectifying circuit arrangement for effecting good television reception.

25 The circuits according to the present invention have all these features necessary for good operation and more particularly the present invention is directed to complete elimination of the carrier-frequency-oscillations in the circuits 30 after-connected to the rectifying stage.

In the accompanying drawing embodiments of the circuits according to the present invention are shown.

Fig. 1 shows a television receiving circuit according to the present invention and

Fig. 2 represents a diagram of the circuit shown in Fig. 1 showing the relations between the potential at the grid of the Braun tube and the frequencies to be transmitted.

40 As well known, the increasing slope of the characteristic with increasing amplitudes is performed by use of anode bend rectification, primarily with short-circuiting of the anode circuit. A three-pole tube 1, with the aid of a tapping 3, 45 is so adjusted to a battery 2 having a comparatively low potential of approximately 30 volts that the anode current is just caused to cease. The modulated carrier wave is supplied by means of the transformer 4. In the anode circuit there 50 is provided a resistance 5, which is made so small in its ohmic value that in spite of the inherent capacities it is effective also at the highest image-frequencies. An after-connected amplifying tube 6 is coupled with the anode of tube 1 in direct fashion. The grid 7 is preferably passed

out separately through the glass wall. The cathode of the amplifier 6 is earthed, and the tube itself is a pentode with large amplification factor.

In both anode circuits, that of the detector 1 and that of the after-amplifier 6 with its anode resistance 8, there arise both rectified modulated oscillations as well as considerable traces of the carrier-oscillations. The anode circuit of the end amplifier is not connected through to the Braun 10 tube 9 directly, but the carrier wave is previously eliminated by a capacitative compensation. For this purpose a differential condenser 10/11 is connected with one pole to the anode circuit 8 and with the other pole to the grid 7 of the amplifier 6. The rotor 12 may then be so adjusted that the carrier wave disappears entirely. A condition for this is that there is not caused by reason of the useful circuit 13/14 any inadmissible load on the condenser portion 10/12. Merely 15 the image currents flow through the circuit 13/14. According to the invention, the circuit is produced as series connection of a choke 13 and a damping resistance 14. It is then possible to find a choke operating in series resonance with 20 the inherent capacities 15 at the maximum image frequency. As regards all frequencies which are still higher, i. e., more particularly beyond the side band of the carrier wave, the choke then represents a very high resistance, and accordingly 25 30 the compensation by the differential condenser is very good for the carrier wave.

Fig. 2 shows a diagram showing the relationship (experimentally obtained) between the oscillation potential e at the control grid 9 of the 35 image reproducing device of the circuit of Figure 1 over a wave-length band between 50 metres and approximately 300 metres. The carrier wave-length was 100 m., side band about 50 to 150 m., the number of lines per frame was 400 40 and the maximum video frequency f_B was 1.6×10^6 which corresponds to about 200 m. Choke 13 had a winding surface of 100 x 50 mm., and was arranged to resonate at frequency f_B . The oscillation potential e at the grid 9 of the 45 cathode ray tube was substantially zero throughout the entire carrier wave band from the lower side-band frequency $f_T - f_B$ to the higher side-band frequency $f_T + f_B$ and then rose in the form of a resonance hump in the neighbourhood of 50 the frequency f_B . The shape of the resonance hump at frequency f_B can be varied by varying the value of resistance 14. Curve a was obtained with the damping resistance 14 at zero, curve b was obtained with resistance 14 at 2,000 55

ohms and curve *c* was obtained with resistance 14 at a still higher value. Consequently by choosing a suitably low value for resistance 14 one can effect a correction of losses in the higher 5 video frequencies and thereby improve the reproduction of the high lights of the reproduced picture.

As regards the anode resistances 8 and 5 there applied the condition of "no angle" in respect 10 of carrier frequency $\pm$ maximum image-point frequency. The final dimensioning of the arrangement is as follows:

	200 lines	400 lines
15 5.....	5,000 Ω	3,000 Ω
8.....	2,500 Ω	1,500 Ω
10/11.....	50 cm.	50 cm.
14.....	About 1,000-3,000 Ω	About 1,000 Ω

20 The neutralisation capacity 16/11 remains constant, independently of the number of lines, so long as the branch 13/8 in the case of maximum image frequency is adjusted to series resonance and at the same time possesses a sufficiently high 25 impedance.

The synchronisation is branched off at the line which is traversed by the most powerful modulation frequencies, as it is there that the amplitude filtering is possible in the most simple 30 fashion. It is preferably performed by a two-pole tube 16 having a free cathode, which operates by way of an adjustable bias 17 on the synchronisation transformers 13. It is preferable 35 and possible to fit this two-pole path into the three-pole tube 1, as merely a very small emission of approximately 2 milliamperes is required in respect of the two-pole tube.

I claim:

1. In combination an electronic amplifier in-

cluding at least an anode, a control grid and a cathode, having an input and output circuit, a filter circuit and means for balancing out carrier frequency oscillations, said filter circuit and said means being arranged in said output circuit, said means for balancing out consisting of a differential condenser having one rotor and two stators, one stator being connected to said input circuit which rectified carrier oscillations with modulation signals are applied to, the other stator being connected to the anode of said amplifier, said rotor being connected to the output terminal of said amplifier, said filter circuit being arranged between said stator connected to said anode and said rotor and having a low impedance to the modulation signals and a high impedance to the carrier oscillations.

2. In combination an electronic amplifier including at least an anode, a control grid and a cathode, having an input and output circuit, a filter circuit and means for balancing out carrier frequency oscillations, said filter circuit and said means being arranged in said output circuit, said means for balancing out consisting of a differential condenser having one rotor and two stators, one stator being connected to said input circuit which rectified carrier oscillations with modulation signals are applied to, the other stator being connected to the anode of said amplifier, said rotor being connected to the output terminal of said amplifier, said filter circuit being arranged between said stator connected to said anode and said rotor and having a low impedance to the modulation signals and a high impedance to the carrier oscillations.

KURT SCHLESINGER.
